UNITED STATES PATENT OFFICE.

FRANK P. NOERA, OF WATERBURY, CONNECTICUT.

DESIGN FOR AN OILER.

SPECIFICATION forming part of Design No. 27,011, dated May 4, 1897.

Application filed February 11, 1897. Serial No. 623,012. Term of patent 7 years.

To all whom it may concern:

Be it known that I, FRANK P. NOERA, a citizen of the United States, residing at Waterbury, in the county of New Haven and State of Connecticut, have invented and produced 5 a new and original Design for Oilers, of which the following is a specification, reference being had to the accompanying drawing, forming a part thereof.

10 The drawing is a perspective illustration of an oiler showing my design.

The leading feature of my design for an oiler consists of a smooth cylindrical body having an enlarged annular bead at its base, 15 an exteriorly-convexed or dome-like top connected by a reverse-curved surface with the upper end of the body, and an upright conical elongated nozzle springing from a disk-like cap at the flattened apex of the dome.

20 The body *a* is cylindrical and smooth, hav-

ing an enlarged annular bead *b* at the base, the body being surmounted by an exteriorly-convexed or dome-like top *c*, connected by a reverse-curved surface *c'* with the top of the body *a*.

25 A long conical nozzle *d* springs from a disk-like cap *d'* at the flattened apex of the dome or top *c*, the whole design presenting a pleasing and graceful combination of curved lines and surfaces.

30 What I claim is—

The design for an oiler, substantially as herein shown and described.

35 In testimony whereof I have signed my name to this specification in the presence of two subscribing witnesses.

FRANK P. NOERA.
